Specification for Design.

Patented Sept. 9, 1913.

Application filed July 14, 1913. Serial No. 779,056. Term of patent 14 years.

To all whom it may concern:

Be it known that I, CHARLES BLESCH, a citizen of the United States, residing at Newport, in the county of Campbell and State of Kentucky, have invented a new, original, and ornamental Design for Plates for Burial-Caskets, of which the following is a specification, reference being had to the accompanying drawing, forming part thereof.

My new, original and ornamental design for a plate for burial-caskets is shown in the accompanying drawing, in which,

Figure 1 is a front elevation of a plate for burial-caskets, showing my new design. Fig. 2 is a cross-section of the same on the line 2—2 of Fig. 1; and, Fig. 3 is a cross-section of the same on the line 3—3 of Fig. 1.

I claim:

The ornamental design for a plate for burial-caskets, as shown.

CHARLES BLESCH.
